UNITED STATES PATENT OFFICE.

OGDEN MALLORY, OF AUBURN, CALIFORNIA.

COMBINED PAD-BUCKLE AND TRACE-CARRIER.

SPECIFICATION forming part of Letters Patent No. 320,569, dated June 23, 1885.

Application filed March 9, 1885. (No model.)

To all whom it may concern:

Be it known that I, OGDEN MALLORY, of Auburn, county of Placer, and State of California, have invented an Improvement in Combined Pad-Buckle and Trace-Carrier; and I hereby declare the following to be a full, clear, and exact description thereof.

My invention relates to an improved pad-buckle and trace-carrier for harness; and it consists in the combination of devices herein-after described and claimed.

Referring to the accompanying drawings, Figure 1 is a perspective view of my combined pad-buckle and trace-carrier. Fig. 2 shows its application. Fig. 3 is a vertical section of same. Fig. 4 is a modified form.

A is the pad-buckle, and B the trace-carrier. The former consists of a rectangular buckle-frame, *a*, across the center of which is a body bar or piece, *a'*. This piece does not lie in the same plane as the frame, but is depressed by reason of having outwardly-turned or angular ends, which join the frame. It is provided with a tongue, *a''*, for engaging the pad or saddle strap.

The trace-carrier consists of a base-piece, *b*, joining at one end the frame *a* of the buckle, and having at its other end an inwardly-inclined loop, *b'*, and on its outer or front surface the bent piece *b''*, forming a plain loop, *b'''*.

C is the pad-strap. This passes behind the end bar of frame *a*, over the depressed center *a'*, engaging its tongue *a''* behind the base-piece *b* and through loop *b'*. It will thus be seen that the course of strap C is practically a straight one, the advantage of which is in preventing any bending or kinking, which has a tendency to wear the strap, and also to make the harness lie more snugly.

D is the trace, which passes through the loop *b'''*, and *d* is a loop on said trace for a breeching-strap, when such is used.

A modification of the device is shown in Fig. 4, where the trace-carrier B is united with an ordinary buckle. In this case the loop *b'* on the trace-carrier is straight and receives the billet *e* of the belly-strap. The billet of the pad or saddle strap does not pass

through the loop *b'*, but through a keeper, *e'*, on the inner side of the billet *e*. This is required to keep the pad-strap as straight as possible.

In Figs. 2 and 3 the billet of the pad-strap, after passing through loop *b'*, is to be connected with the billet of the belly-strap by any ordinary buckle; or, as is obvious, for one side of the harness it may be extended or continued to form the belly-strap; or, again, the strap C may be considered as the belly-strap for one side of the harness, or the billet of said strap for the other side, and may be connected with a short pad-strap above the trace-carrier and buckle.

As my invention consists, broadly, in the union of a pad-strap buckle with a trace-carrier, I do not wish to confine myself to the precise construction of the particular buckle herein described, with the particular trace-carrier, for, as is shown in Fig. 4, an ordinary buckle may be used with the trace-carrier, and, as is obvious, the particular buckle or a common buckle may be used with any other form of trace-carrier, a loop, or even a buckle device, behind which, on account of the depressed center of the buckle, the pad-strap is adapted to pass in an approximately straight course.

Having thus described my invention, what I claim as new, and desire to secure by Letters Patent, is—

As an improved article of manufacture, a combined pad-strap buckle and trace-carrier, consisting of the buckle A, having a frame, *a*, and a depressed transverse center piece, *a'*, with a tongue, *a''*, and the trace-carrier B, having a base-piece, *b*, connected with and in the same plane as the frame of the buckle, an inwardly-inclined end loop, *b'*, and a front piece, *b''*, bent to form a plain loop, *b'''*, substantially as herein described.

In witness whereof I have hereunto set my hand.

OGDEN MALLORY.
